(57) **CLAIM**

The ornamental design for a container with movable poptop closure, as shown and described.

DESCRIPTION

FIG. 1 is a top perspective view of the preferred embodiment of the container showing the present invention with the closure shown in the open position;

FIG. 2 is a top view thereof;

FIG. 3 is a left side view thereof with the right side view being a mirror image thereof;

FIG. 4 is a front view thereof;

FIG. 5 is a rear view thereof;

FIG. 6 is a bottom view thereof;

FIG. 7 is a top view thereof with the closure shown in the closed position;

FIG. 8 is a top perspective view of the alternate embodiment of the container showing the present invention with the closure shown in the open position;

FIG. 9 is a top view of the container of FIG. 8;

FIG. 10 is a left side view of the container of FIG. 8 with the right side view being a mirror image thereof;

FIG. 11 is a front view of the container of FIG. 8;

FIG. 12 is a rear view of the container of FIG. 8;

FIG. 13 is a bottom view of the container of FIG. 8; and,

FIG. 14 is a top view of the container of FIG. 8 with the closure shown in the closed position.
